ELECTRICALLY OPERATIVE STERILIZER

Filed Jan. 2, 1930

UNITED STATES PATENT OFFICE

DAVID WILLIAM HERBERT, OF BROOKLINE, PENNSYLVANIA, ASSIGNOR OF ONE-HALF
TO WILLIAM ROY HOOVEN, OF BROOKLINE, PENNSYLVANIA

ELECTRICALLY-OPERATIVE STERILIZER

Application filed January 2, 1930. Serial No. 417,941.

My invention is designed for installation upon the wall of a bathroom to temporarily receive and sterilize toothbrushes. However, the embodiment of my invention hereinafter described is adapted for sterilizing any article which will fit within its casing, for instance, dental and surgical instruments, and may be portable.

My invention includes the various novel 10 features of construction and arrangement hereinafter more definitely specified.

In said drawings, Fig. I is a front elevation of a convenient embodiment of my invention.

15 Fig. II is a fragmentary vertical sectional view taken on the line II, II, in Fig. I. In said figures; the casing 1 is conveniently formed of pressed sheet metal and divided into compartments 2 and 3 by a foraminous 20 partition 5, conveniently formed of wire screening of, say one-quarter inch mesh. Said casing has the hinged door 6 for said compartment 2, and which may be adapted to open downwardly, as indicated, or be 25 otherwise connected with said casing and provided with any suitable temporary fastening means for holding it shut when desired. Said compartment 2 is conveniently provided with racks 7 which may be formed 30 of pressed sheet metal, soldered at their opposite ends to the walls of said casing or otherwise secured therein. Said racks 7 are adapted to support toothbrushes 10 or other articles to be sterilized.

35 The sterilization above contemplated is conveniently effected by inclosing the articles to be sterilized in said chamber 2 and heating the atmosphere therein to a temperature of, say, 200° F. for a period of say 40 two minutes. Such heating effect may be conveniently attained by electrical apparatus inclosed in said compartment 3 by the lid 11 which is preferably detachably connected 45 with said casing 1. Said apparatus comprises a circuit including means for manually closing it in connection with a source of electrical energy and means for automatically breaking said circuit at the expiration of a period 50 of time, the extent of which may be adjust-

ably predetermined and varied, as hereinafter described.

Said circuit includes the conductors 12 and 13, extending exterior to said casing 1, and which may be permanently connected to a 55 house circuit if said casing is mounted as a fixture upon a wall, or, said conductors may terminate in an ordinary screw plug adapted for detachable engagement with any base receptacle or other similar fitting, if said casing is portable. 60

The electrical apparatus in said casing is conveniently mounted upon a base 15 formed of porcelain, bakelite or other suitable insulating material which may be detachably 65 rigidly secured in said compartment 3 by screws 16. Said conductor 12 extends to the metal bearing 18 of the push switch plunger 19 having at its outer end the push button 20, of insulating material, by which it may 70 be manually operated, by thrusting it inwardly against the pressure of the spring 21 which normally stresses it to the position shown. Said bearing 18 is rigidly connected with said insulating base 15 by the screws 22. Said 75 conductor 13 is connected, by the binding post 23, with the bimetallic strip 26, one end of which it holds upon the lug 27 of said base 15, so that the opposite end of said strip is free to vibrate. Said strip carries the heating coil 28 which is connected at one end to 80 said binding post 23 and at the other end to the stationary spring terminal 29 of said push switch, the latter connection including the flexible conductor 30, the binding post 31, and 85 conductor 32; said binding post 31 being mounted in the lug 33 of said base 15. Said terminal 29 is detachably rigidly connected with said base 15 by the screw 34, the end 35 of said terminal being bent downwardly into 90 a recess 36 of said base 15, to prevent it from being accidentally displaced. Said supply conductor 13 is also connected, from said binding post 23, to one end of the heating coil 37 which is wound with its convolutions 95 in spaced relation in a spiral groove 38 on the spool 39 which is conveniently formed of molded ceramic and detachably mounted between the lugs 42 and 43 on said base 15. 100

The opposite end of said coil 37 is connected to said stationary terminal 29.

Said binding post 31 is also connected with one end of the electromagnet coil 45, the opposite end of which is connected to the axially adjustable switch terminal screw 46 which is mounted in said lug 33 and secured in adjusted position therein by the nuts 47 so as to afford more or less gap 48 between the end of 10 said terminal screw 46 and the free end of said bimetallic strip 26, which strip, when heated, bends toward said screw until it contacts therewith and closes the circuit through said electromagnet coil. It is to be understood 15 that the length of time required to effect such closure corresponds with the length of said gap 48, which may be varied by adjustment of the terminal screw 46.

Said electromagnet coil 45 is conveniently 20 supported by its core 49, which is engaged by the screw 50 extending through the lug 51 on said base 15.

Said electromagnet core 49 is in registry 25 with the armature 52 which has the stem 54 mounted to reciprocate in said metallic bearing 18 and encircled by the spring 55 which bears against the cross pin 56 in said stem and tends to thrust the latter into engagement with the shoulder 57 on the plunger 19, so as 30 to hold the latter in its inwardly pushed position in which said plunger 19 contacts with said terminal 29, to close the circuit through both the heating coils 28 and 37. When thus energized, both of said coils 28 35 and 37, of course, tends to heat the atmosphere within the casing 1. However, the coil 28 being directly applied to the metallic strip 26, the latter is thus subjected to a higher temperature than that of the surrounding 40 atmosphere in said casing, and with the effect of closing the circuit through said magnet coil 45 in less time than if said coil 28 were not in immediate contact with said metallic strip 26. When said contact between the bi- 45 metallic strip 26 and the terminal screw 46 is effected; said magnet coil 45 is energized to attract the armature 52 and shift it toward the core 49, thus retracting the armature stem 54 from engagement with the shoulder 57 50 on the plunger 19; thus permitting the spring 21 to thrust said push switch plunger 19 outwardly and break the circuit between said plunger and the spring terminal 29; thus de- 55 energizing both of said coils 28 and 37 and thus stopping the heating operation at the expiration of a predetermined time from the instant when the button 20 was pushed to close the heating circuit. As above indicated, 60 two minutes is adequate time in which to sterilize toothbrushes, for with an ordinary 110 volt, 60 cycle A. C. supply of electrical energy, the atmosphere within the casing 1 is raised to 200° F., in that time. Of course, 65 both the time and temperature of the steriliz-

ing operation may be varied, as above indicated.

Therefore, I do not desire to limit myself to the precise details of construction and arrangement herein set forth, as it is obvious that various modifications may be made therein without departing from the essential features of my invention, as defined in the appended claims.

I claim:

1. A dwelling fixture including a sterilizer casing attached to a wall and adapted to removably inclose a tooth brush; and means adapted to heat the atmosphere in said casing to such a degree as to sterilize 80 said brush, including conductors adapted to supply electric energy from the dwelling circuit to said casing, a heating coil in said casing, and a switch movable to close and open the circuit thru said coil; said switch being manually operative to close it and initiate the sterilizing operation and having a spring continually tending to open said switch; means arranged to detain said switch in closed position and to automatically release it and stop the sterilizing operation after a predetermined interval, including an armature in cooperative relation with said switch, an electromagnet in cooperative relation with said armature, and a thermostatic 85 switch controlling the circuit thru said electromagnet; whereby, when said switch is manually closed to initiate the heating operation, said thermostatic switch is heated and ultimately closes the circuit thru said electromagnet and thereby operates said armature to release said manually operative switch and permit it to be opened by its spring to break all of the circuits and terminate the sterilizing operation.

2. Apparatus as in claim 1, including means, in said casing, adjustable to vary the time required to effect the operation of said thermostatic switch and thus control the time of continuance of the sterilizing operation.

3. In a sterilizer; the combination with a casing; of means adapted to support an article to be sterilized in said casing; a movable closure for said casing; electrically operative heating means in said casing, including a main heating coil, a manually operative switch, and supply conductors including said coil in circuit with said switch; a spring continually tending to open said switch and break said circuit; means adapted to restrain said spring and detain said switch in closed position, including an armature; means arranged to release said switch and spring, by movement of said armature, including an electromagnet, a thermostatically operative switch, and conductors adapted to include said magnet coil and latter switch in a shunt circuit around said heating coil; whereby, when said manually operative switch is closed, it is temporarily, automati- 130

cally, held in closed position; said main heating coil is energized and heats the atmosphere in said casing, and said thermostatic switch, causing the latter to alternately close the circuit through said electromagnet coil, and thereby release said manually operative switch, and break all of said circuits, thus terminating the heating operation.

4. In a sterilizer; the combination with a casing; of foraminous means dividing said casing in two compartments; means adapted to support an article to be sterilized in one of said compartments; a movable closure for that compartment; a separate movable closure for the other compartment; electrically operative heating means in the latter compartment, including a main heating coil, a manually operative switch, supply conductors including said coil in circuit with said switch, and means connected with said switch and extending exterior to said casing, whereby said switch may be operated when said casing is closed; a spring continually tending to open said switch and break said circuit; means adapted to detain said switch in closed position, when manually closed against the stress of its spring, including an armature; means arranged to release said switch by movement of said armature, including an electromagnet in cooperative relation with said armature, a thermostatically operative switch, including a flexible bimetallic strip, an adjustable terminal adapted to cooperate with said strip, conductors adapted to include said magnet coil and terminal in a shunt circuit around said heating coil, an auxiliary heating coil carried by said strip, and electrical conducting means connecting said auxiliary heating coil in another shunt circuit around said heating coil; an auxiliary heating coil carried by said strip, and electrical conducting means connecting said auxiliary coil in another shunt circuit around said main heating coil; whereby, when said manually operative switch is closed, it is temporarily, automatically, held in closed position; said main heating coil and auxiliary heating coil are both energized from the same source of electrical energy and heat the atmosphere in said casing, but heat, to a greater degree, said bimetallic strip, causing the latter to bend into contact with said terminal, close the circuit through said electromagnet coil, release said manually operative switch, and break all of the circuits simultaneously, thus terminating the heating operation; said terminal being adjustable to predetermine the duration of each heating operation initiated by the closure of said manually operative switch.

5. In a sterilizer; the combination with a casing; of foraminous means dividing said casing in two compartments; means adapted to support an article to be sterilized in one of said compartments; a hinged closure for that compartment; a separately removable closure for the other compartment; electrically operative heating means in the latter compartment, including a main heating coil, a manually operative switch, supply conductors in-

cluding said coil in circuit with said switch, and push means connected with said switch and extending exterior to said casing, whereby said switch may be operated when said casing is closed; a spring continually tending to open said switch and break said circuit; means adapted to detain said switch in closed position, when manually closed against the stress of its spring, including a reciprocating stem carrying an armature; means arranged to release said switch, by movement of said armature and stem, including an electromagnet in cooperative relation with said armature, a thermostatically operative switch, including a flexible bimetallic strip, an adjustable terminal adapted to cooperate with said strip, conductors adapted to include said magnet coil and terminal in a shunt circuit around said heating coil, an auxiliary heating coil carried by said strip, and electrical conducting means connecting said auxiliary coil in another shunt circuit around said main heating coil; whereby, when said manually operative switch is closed, it is temporarily, automatically, held in closed position; said main heating coil and auxiliary heating coil are both energized from the same source of electrical energy and heat the atmosphere in said casing, but heat, to a greater degree, said bimetallic strip, causing the latter to bend into contact with said terminal, close the circuit through said electromagnet coil, release said manually operative switch, and break all of the circuits simultaneously, thus terminating the heating operation; said terminal being adjustable to predetermine the duration of each heating operation initiated by the closure of said manually operative switch.

6. Apparatus as in claim 5; wherein all of the electrical elements are mounted upon an insulating base, separable from said casing.

In testimony whereof, I have hereunto signed my name at Philadelphia, Pennsylvania, this seventeenth day of December, 1929.

DAVID WILLIAM HERBERT.
